UNITED STATES PATENT OFFICE

GARDINER C. VOSE, OF ANN ARBOR, MICHIGAN, ASSIGNOR TO INTERNATIONAL RADIO CORPORATION, OF ANN ARBOR, MICHIGAN, A CORPORATION OF MICHIGAN

DESIGN FOR A RADIOCABINET

Application filed May 1, 1933. Serial No. 47,945. Term of patent 3½ years.

To all whom it may concern:

Be it known that I, GARDINER C. Vose, a citizen of the United States of America, residing at Ann Arbor, in the county of Washtenaw and State of Michigan, have invented a certain new, original, and ornamental Design for a Radiocabinet, of which the following is a specification, reference being had

therein to the accompanying drawing, forming a part thereof, in which the figure is a perspective view of a radiocabinet showing my new design.

I claim:

The ornamental design for a radiocabinet substantially as shown.

GARDINER C. VOSE.
